BATHER'S VANITY CASE

Original Filed June 9, 1926

Inventor
Thomas R. McDonald,

By Clarence O'Brien.

Attorney

Patented May 29, 1928.

UNITED STATES PATENT OFFICE.

THOMAS R. McDONALD, OF COLUMBUS, OHIO.

BATHER'S VANITY CASE.

Application filed June 9, 1926, Serial No. 114,746. Renewed March 22, 1928.

This invention relates to vanity cases that are specifically adapted for use by bathers and has for its primary object to provide a case that may be readily attached to the bathing suit, and that is so constructed as to be water proof so that the face powder, rouge, lip stick, and other article disposed therein will not become ruined by water or moisture regardless of the length of time that the same may remain submerged within the water.

The invention further aims to provide a vanity case of the aforementioned character that is exceedingly simple in construction, but yet very rigid and that is not liable to become readily marred or broken even though subjected to rough usage.

In the drawing wherein like reference characters indicate corresponding parts throughout both of the views:

Figure 1 is a view of the case in longitudinal cross section, the dotted lines representing the lid of the case when removed from the case proper and also the cosmetic carrying receptacle in outwardly swung position to enable the contents thereof to be used, and

Figure 2 is a fragmentary plan view of the case disclosing more clearly the cosmetic receptacle and the hinged connection between the receptacle and the body of the case proper.

Now having particular reference to the drawing, the numeral 5 represents the body of the vanity case which is of circular formation and constructed preferably of fibre, ivory, or other suitable water proof material. The open side of the body 5 is exteriorly rabbeted and threaded for receiving in a flush manner the internally threaded rim 6 of the circular lid 7 preferably of the same material as said body 5.

Arranged upon the inner face of the lid 7 is a mirror 8, and a comb 9 necessarily of arcuate formation.

Arranged within the body 5 of the case is a circular cosmetic receptacle consisting of a body 10 and a lid 11. Said body 10 is formed or provided with a suitable number of desirably shaped pockets 13 for receiving powder, rouge, lip stick, eyebrow pencil, etcetera.

Directly adjacent the body of the recep-

tacle the same is formed with a pair of spaced lateral ears 12—12 the inner ends of which are arranged within notches of the case body 5 directly at the open end thereof, said ears being formed with openings through which extend the opposite ends of a pivot pin 13 embedded within the material forming the body so as to permit the cosmetic receptacle to be swung outwardly of the body into horizontal position with respect thereto as clearly disclosed by the dotted lines in Figure 1.

The lid 11 of the cosmetic receptacle is so pivoted to the body of the receptacle as at 14 to permit the same to be swung to open or closed position as disclosed in Figure 2.

In order that the case may be attached to the usual waist encircling belt of the generally conventional designs of bathing suits, the bottom wall of the case body 5 is formed with a relatively elongated bail 15 that extends horizontally across the body so as to permit the belt to be disposed between the bail and said body in an obvious manner. Other means may be provided however to facilitate the proper attachment of the case to the suit of the bather, the present means being disclosed merely for purposes of illustration.

Preferably, though not necessarily the body 5 and lid 7 are interconnected by a chain length 16, so as to prevent the loss of the lid when the same is detached from the body to permit the use of the cosmetics within the receptacle hingedly mounted with respect to the body so as to normally be positioned therein when not in use.

It will thus be seen that I have provided a highly novel, simple and efficient form of vanity case for bathers that is well adapted for all the purposes heretofore designated and even though I have herein shown and described this invention as consisting of certain detail structural elements, it is nevertheless to be understood that departures may be had therefrom without effecting the spirit and scope of the appended claim.

Having thus described the invention, what I claim is:—

As a new product of manufacture, a bather's vanity case comprising a substantially circular cosmetic holder embodying an open top receptacle and a swingably mount-

ed closing plate therefor, said receptacle being provided on one side with a pair of outstanding attaching ears, and a water-proof housing for said cosmetic holder comprising 5 a circular hollow body open on one side and having its rim provided with external screw threads, a pivot pin carried by the inner periphery of the rim, the aforesaid ears being connected with said pin whereby to permit 10 said holder to be swung into the body or

forwardly at right angles in order that the holder may rest against said rim to be supported in said right angular position, and removable cover for the body having a screw-threaded flange threaded onto said rim, said 15 cover serving to retain said holder within the body.

In testimony whereof I affix my signature.

THOMAS R. McDONALD.
